UNITED STATES PATENT OFFICE.

LEWIS G. ROWAND, OF BROOKLYN, NEW YORK, ASSIGNOR TO THE NEW JERSEY ZINC COMPANY, OF NEW YORK, N. Y., A CORPORATION OF NEW JERSEY.

MAGNETIC ORE-SEPARATOR.

1,303,396.

Specification of Letters Patent.

Patented May 13, 1919.

Application filed June 21, 1917. Serial No. 176,027.

To all whom it may concern:

Be it known that I, LEWIS G. ROWAND, a citizen of the United States, residing at Sea Gate, borough of Brooklyn, in the county of 5 Kings, State of New York, have invented certain new and useful Improvements in Magnetic Ore-Separators; and I do hereby declare the following to be a full, clear, and exact description of the invention, such as 10 will enable others skilled in the art to which it appertains to make and use the same.

The present invention relates to ore separators of the type in which the ore in finely divided condition is carried by a conveyer 15 belt into a magnetic field which is so disposed as to lift the magnetic particles out of the gangue and against the bottom of another conveyer belt disposed at right angles to the ore conveyer and operating to divert these lifted magnetic particles laterally with respect to the ore conveyer and finally discharge them into a suitable receptacle. A 20 separator of this general type is disclosed in U. S. Letters Patent No. 596,719, issued to me January 4, 1898.

It is an object of the present invention to improve both mechanically and magnetically the structures whereby the electromagnetic field is set up and maintained.

30 It is a further object of the invention to so group the electromagnetic elements as to provide a plurality of magnetic fields of different intensity and, in fact, of different character, whereby, as I have found, a more 35 advantageous separation of ore is obtainable, particularly in the case of certain zinc ores.

There are certain other object to be accomplished and certain inherent advantages 40 in the apparatus of the present invention, all of which will be appreciated by those skilled in this art, and to the more important of which reference is particularly made in the following detailed description.

45 In the accompanying drawings—

Figure 1 is a side elevation of one embodiment of the present invention;

Fig. 2 is a plan view of the same, certain of the underlying elements being omitted 50 for the sake of clearness;

Fig. 3 is a transverse elevation on the line 3—3 of Figs. 1 and 2;

Fig. 4 is a transverse elevation on the line 4—4 of Figs. 1 and 2;

Fig. 5 is a plan view on the horizontal section 5—5 of Fig. 1, a part of the ore-carrying belt being broken away to disclose elements beneath;

Fig. 6 is a rear end elevation of the apparatus;

Fig. 7 is a horizontal section through the electromagnets on the line 7—7 of Fig. 4;

Fig. 8 is a detail of the pole faces of these electromagnets; and Fig. 9 is a detail of one pole shoe.

In the embodiment illustrated, the machine has for its foundation, girders 1 and 2, each comprising a pair of channel irons arranged back to back and spaced apart by a plurality of metal fittings 3 and 4 arranged in pairs. Bolts 5 hold the channels against these fittings. The upper portion of each fitting has a projecting shelf 6 which rests upon the upper flange of the adjacent channel. Between each pair of fittings a 70 standard or pedestal 7 can be received and firmly clamped not only by the bolts 8, provided for that purpose, but also by the bolts 5 which anchor the fittings to the channels. These pedestals are used for supporting certain parts of the apparatus as hereinafter described more in detail.

At the front end of the machine is a rectangular framework 9, superimposed on which is a smaller framework 10, whereon is 85 mounted the ore feeding hopper 11. Ore from the hopper is fed in regulated amount by a feed roller suitably driven and for which no novelty is claimed herein, the ore being finally delivered to a substantially 90 horizontal belt 12 of duck or other suitable fabric, stretched rather tightly between cylindrical drums 13 and 14, one of which is at the rear end of the machine and suitably driven, as by a belt pulley 15, and the other of which is carried in a pair of bearings 16, each mounted to slide on a pair of horizontal supporting bars 17. A counterweight 18 and a flexible tension band 19 serve, as shown in Fig. 1, to keep the ore carrying belt suitably taut under all conditions of operation.

In delivering the finely divided ore to the conveyer belt, it should fall upon the belt in a thin, well distributed layer, and preferably the particles should at the instant of delivery to the belt, be traveling in the same direction as the belt and at about the same

speed. This is easily arranged for by adjustable deflectors and other like expedients well known in the art.

The electromagnetic device into the field or fields of which the ore is first transported by the conveyer belt has vertically disposed coils or windings 20 and 21 which are provided respectively with cylindrical iron cores 22 and 23 suspended by bolts from a magnetizable yoke 24. But in addition to the cylindrical cores on which the coils are mounted, there is a third or intermediate core or pole 25 integral with or attached to yoke 24, and preferably of rectangular cross-section, as shown in Fig. 7, but with an enlarged bottom end, as shown in Fig. 8, to form constricted pole tips 26 and 27, which respectively are positioned opposite the similarly shaped pole tips 28 and 29 with which 20 the cylindrical cores 22 and 23 are provided, as shown in Fig. 8.

The electrical current in winding 20 is controllable by a rheostat 30, and a similar rheostat 30' is in circuit with coil 21. The two coils 20 and 21 can, if desired, be connected in series, but I prefer that their circuits shall be independent so that I can, by suitable regulation of the current, make the magnetic flux or field between pole faces 27 and 29 greater than that between pole faces 26 and 28. Coils 20 and 21 are of course so connected as not to neutralize one another, but on the contrary, to supplement one another in magnetizing the intermediate core 25, and the latter is for this reason equal to or larger than the cross-section of the two adjacent cylindrical cores.

With windings 20 and 21 fully energized, there is a strong tendency for the pole faces to approach one another and a heavy lateral strain is thereby put on the bolts whereby the cores are supported. Any slight variation in the distance between adjacent pole pieces would, of course, have a pronounced effect on the magnetic field, and I therefore adequately protect the electromagnetic structure by abutments of wood introduced in each air gap. The wood also keeps dirt out of the gap.

Each abutment comprises a pair of wedge-shaped blocks 31 and 31', between which is interposed a flat strip 32. Vertical bolts 33, threaded into the pole tips, serve to hold the tapering blocks firmly against the inclined face of the metal pole and tightly wedged against the intervening flat strip 32. The lower edge of this flat strip is flush with the bottom face of the pole tips, and by its presence gives a smooth bearing surface for the transverse belts hereinafter described. A wooden block 34, bolted to each wedge block, as shown in Fig. 7, gives greater security to the structure, and a rounded face for the belt.

It is, of course, the function of this com-

bined electromagnet to lift from the upper face of the adjacent conveyer belt the more easily magnetizable particles or grains of the ore, and, if desired, the magnetic field between the pole faces 26 and 28 may be weaker than the magnetic field between pole faces 27 and 29, thereby giving a selective action on particles which have different capacities for magnetization. As a means for receiving the particles and transporting them laterally for deposit in a suitable receptacle or chute, there is provided under each air gap of this electromagnetic unit a discharging belt 35. Each of these belts is mounted as shown in Fig. 4 on three drums 36, 37 and 38. Drum 36 is on a shaft to which a pulley 39 is secured for driving. The bearings for drum 38 are adjustable along a horizontal bar 40 to vary the length of the conveyer belt and thereby compensate for its stretching. Each discharging belt 35 slides along the under-face of the electromagnetic structure just beneath one of the air gaps, and when an ore particle is lifted by the electromagnets, it strikes against the under-face of discharging belt 35 and thereby is conveyed at right angles to its previous path and ultimately is delivered into a hopper at the side of the main or ore conveyer belt 12.

In the embodiment illustrated in Fig. 4, two hoppers are provided, a small one marked 41 being positioned just under the edge of the ore conveyer to collect such particles or grains of non-magnetic material as may become entangled with the truly magnetic material, and thereby diverted from the ore-laden belt. The truly magnetic material is, however, carried over into a larger hopper 42, or, at least is given such impetus in that direction that when released from the influence of the magnetic field, it falls therein. A hood 43 may be provided at the extreme outer end of this hopper to catch such particles as might otherwise be projected beyond the hopper. This hood can be pivotally mounted at 44 with a stud and wing nut to govern the distance of its front edge from the adjacent conveyer and pulley.

As a means for prolonging the time during which the magnetizable particles are under the influence of the magnetic field, and thereby insuring their delivery beyond the tangential hopper 41, I provide all four of the pole faces with a tapering lateral projection 45, somewhat after the principle disclosed in my above identified Patent No. 596,719. There is, therefore, a gradual diminution of the magnetic effect on the particle as it is moving laterally away from the electromagnet and into the receiving hopper, and with proper adjustment of conveyer speeds, electromagnetic strength and size and position of hoppers, there is no danger of a truly magnetizable particle

dropping back on ore conveyer 12 or into hopper 41 instead of into hopper 42.

For reasons which will now be apparent, the double electromagnetic unit above described must be maintained at a proper and relatively definite height above the ore conveyer 12, and to attain this end, there is provided a drum or roller 46 (Fig. 4) to support the ore conveyer at a definite height 10 under the electromagnetic unit, and the unit itself is adjustably supported from above on a plurality of bolts 47. Anchoring lugs or jacks, indicated somewhat diagrammatically at 48 and 49 (Fig. 4), may, by engagement 15 with the vertical steel support columns 50 and 51, serve to steady or anchor the lower end of the electromagnetic unit.

As indicated in the plan view (Fig. 5), each discharging belt 35 has its own pair of 20 hoppers 41 and 42, and as both the belts 35 can with convenience be driven from the same pulley 39 (Fig. 2), it is advantageous to have all four of these hoppers on the same side of the machine, even though the 25 material gathered by one pair may be somewhat different in grading from the material gathered by the other pair.

The mechanism above described, while possessing the advantages of low initial cost, 30 high magnetic efficiency and the like, and while adequate for taking from the finely divided ore mixture its more highly magnetic particles, does not, however, take from the charge on the ore conveying belt all of 35 the particles which are susceptible to magnetic influence. I therefore find it expedient to provide another and more powerful electromagnetic unit, and sometimes more than one, which is positioned beyond the 40 unit above described and works on a different principle, and one more nearly approaching the disclosure of U. S. Letters Patent No. 784,502, issued to me on March 7, 1905.

45 In this second electromagnetic unit and succeeding ones, if more than one is used, the lines of magnetic force are caused to pass directly through the conveyer belt, but one pole face is more effective than the 50 other, as by being of smaller area and consequently carrying a more dense magnetic flux. With such an arrangement an extremely powerful effect can be produced, and those particles of ore which are but 55 faintly magnetizable can be lifted from the ore conveyer against a discharging belt and so can be diverted and transported laterally for deposit in a hopper.

Considering more in detail this second 60 electromagnetic unit, it may be described as comprising a lower coil 52 with upstanding rectangular pole pieces 53 and 54 of generous cross-section over which the ore conveyer slides in passing from drum 13 to 65 drum 14. Superimposed above coil 52 is a

second and similar coil 55 energized, if desired, by the same current and having depending pole pieces 56 and 57, each of which carries a removable rectangular pole point 58 (Fig. 9) seated in a recess in the pole 70 face, but having one of its edges opposed to the underlying flat topped pole face of the lower coil and thereby giving a greater magnetic density above the ore belt than below it, and causing the magnetizable particles 75 to lift out of the gangue toward the edge of this removable pole point. With this electromagnetic unit, each discharging belt 59 is carried on three drums 60, 61 and 62 (Fig. 3), drums 60 and 62 being adjustable 80 along studs 63 and 64 to compensate for stretching, and wear of the belt. Belt 59 is driven from a pulley 65 on the same shaft as drum 60.

The removable pole point 58 may have a 85 tapering nose or tip 66, as shown in Fig. 3, for the purpose of graduating the release of the magnetized particle during its travel with discharge belt 59. This removable point may be held in position by bolts 67 90 (Fig. 9) and may be shod with curved bronze fittings or shoes 68 and 69 to give a good working curvature to discharge belt 59, and to prevent undue wear on the belt as it slides over the lower corner of the 95 point. The pole point is so arranged that it can be turned around in its socket to present a new working edge whenever the old edge becomes so badly worn as to require replacement. With this electromagnetic unit, 100 as with the one first described, there may be a small hopper 70 for the tangles and a large hopper 71 with an adjustable hood 72 for the other deflected particles.

Referring to Fig. 5, it will be seen that all 105 of the hoppers for the first electromagnetic unit are on one side of the machine, and that for the succeeding electromagnetic unit there is a discharge, first to the right of the ore belt and then to the left. I have found 110 that when the ore goes under the first electromagnetic unit, the entire charge is so influenced by the magnets and the discharge belts that it shifts over to some extent on the ore conveyer, thereby giving an unequal distribution of the remaining ore and gangue. I compensate for this by arranging the next discharging belt to deliver to the other side of the machine, thus pulling the gangue back to approximately an even 115 distribution on the ore conveyer. The next discharge belt may properly be to the left 120 of the machine as shown.

When coils 52 and 55 are connected in 125 series, as shown, I prefer to control them by a pair of rheostats 73 and 74 (Fig. 5), one located on each side of the machine, but both being connected together by a single operating shaft so that on which ever side of the machine the operator may stand, he can 130

conveniently and with nicety adjust the magnetizing power of these combined electromagnetizing coils.

With the coils fully magnetized, there is of course an enormous pull of one on the other, and to reliably keep them apart and at just the desired distance, I make use of supporting standards and jacks. The standards 7, four in number, are adequately secured at their lower ends as above described, and each of them carries a pair of nuts 75 between which is clamped one end of a yoke or frame 76 which may be of bronze, and which supports one end of the lower coil 52 10 and its core and poles. To the threaded upper end of each standard 7 is fitted a bronze cap 77 to serve as a jack and having its upper rounded end fitted to a bracket or frame 78 whereby the upper coil and its 15 pole pieces are supported. The weight of the upper coil and its adjuncts takes all slack or back lash out of the joints and threads, and as the entire supporting structure is of generous proportions and rugged 20 design, the presence or absence of the powerful magnetic field between the pole pieces, will not appreciably change the air gap and an adjustment once made can be relied on irrespective of manipulations of current 25 strength.

With the arrangement above described, the air gap for the second discharging belt of the unit may, if desired, be less than the preceding air gap, for by manipulation of 30 the jacks any one of the four supporting corners of the upper coil, can be raised or lowered to meet the exigencies of practical operation, such as change in the character or fineness of the ore discharge. The poles 35 40 56 and 57 are mounted on hubs 79 and 80 of the upper magnet core to permit this.

While I am aware that various changes in detail may be made in the apparatus without departing from the spirit of the present 45 invention as defined by the appended claims, the preferred embodiment above described and illustrated in the drawings is one which has been used with success.

I claim:—

50 1. In a magnetic separator, the combination of an ore-conveying belt, an electromagnetic unit positioned entirely above said belt and having in its magnetic circuit a plurality of relatively narrow air gaps, the 55 field strength of each of which may be independently altered, and separate discharge

belts running under each of said air gaps transversely of said ore-conveying belt to laterally convey magnetic particles lifted from the ore-conveying belt at said air gaps. 60

2. In a magnetic separator, the combination of an ore-conveying belt, a magnetic unit positioned entirely above said belt and comprising three magnetic poles spaced apart to form two relatively narrow air gaps 65 and a pair of coils associated with the magnetic poles for producing magnetic flux at the air gaps, means for separately controlling the energization of said coils to permit independent adjustment of the field strength 70 of each of said air gaps, and separate discharge belts running transversely of said ore-conveying belt and positioned under each of said air gaps to laterally convey particles of ore lifted from said ore-conveying belt 75 at said gaps.

3. In a magnetic separator, the combination of an ore-conveying belt, a magnetic unit positioned above said belt and comprising a plurality of separate windings 80 each with a magnetizable core coöperating with a central pole positioned between said coils to form above said ore-conveying belt a pair of relatively narrow magnetic air gaps, the field strength of each of which 85 may be independently altered, and discharge belts running transversely of said ore-conveying belt and each positioned beneath an air gap to laterally convey magnetic particles lifted thereat. 90

4. In a magnetic separator, the combination of an ore-conveying means, an electromagnetic ore-lifting unit positioned entirely above said means and comprising a pair of coils adapted to be independently controlled 95 and each provided with a magnetizable core, a magnetizable pole magnetically coöperating with said cores and positioned between said coils to form a pair of elongated magnetic air gaps, the field strength of each of which 100 may be independently altered, rigid spacers of non-magnetic material filling said gaps and holding said cores and intermediate pole in proper spaced relation and discharging belts running transversely of said ore- 105 conveying means and each positioned beneath one of the air gaps to laterally convey magnetic particles lifted thereat, substantially as described.

In testimony whereof I affix my signature. 110

LEWIS G. ROWAND.
